US00D695721S

(12) **United States Design Patent**
Thompson et al.

(10) **Patent No.:** **US D695,721 S**
(45) **Date of Patent:** **** Dec. 17, 2013**

(54) **EARPHONE**

(71) Applicants: **AAC Acoustic Technologies (Shenzhen) Co., Ltd.**, Shenzhen (CN);
AAC Technologies Holdings Inc.,
Cayman Islands (GB)

(72) Inventors: **Roy Alden Thompson**, Quincy, MA
(US); **Kai Chun Yang**, McLean, VA
(US); **Han Bao**, Shenzhen (CN)

(73) Assignees: **AAC Acoustic Technologies (Shenzhen) Co., Ltd.**, Shenzhen (CN);
AAC Technologies Holdings Inc.,
Cayman Islands (GB)

(**) Term: **14 Years**

(21) Appl. No.: **29/437,146**

(22) Filed: **Nov. 14, 2012**

(51) **LOC (9) Cl.** **14-01**
(52) **U.S. Cl.**
USPC **D14/223**

(58) **Field of Classification Search**
USPC D14/223; D24/174; 181/129, 130, 135;
379/430, 431; 381/380, 381, 382;

(57) **CLAIM**

The ornamental design for an earphone, as shown and described.

DESCRIPTION

FIG. 1 is an isometric view of an earphone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The shade lines in the figures show contour and not surface ornamentation.
